Primary Examiner — Paula Greene(74) *Attorney, Agent, or Firm* — Nath, Goldberg & Meyer; Jerald L. Meyer(57) **CLAIM**

The ornamental design for a portion of earphone, as shown and described.

DESCRIPTION

FIG. 1 is a front perspective view of a portion of earphone showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown are included for the purpose of illustrating the unclaimed portions of the article and form no part of the claim.
